UNITED STATES PATENT OFFICE

JOHN H. MONTGOMERY, OF OMAHA, NEBRASKA

DISHWASHING MACHINE

Application filed March 5, 1928. Serial No. 259,073.

This invention relates to a dishwashing machine, and has for its object, broadly, to provide a machine for general household use whereby water may be applied to the dishes while confined in a rotating basket for effectively removing grease or other adhering substances, the parts to be arranged convenient for use and requiring very slight attention of an operator.

10 One of the objects of the invention is to provide operating parts which may be actuated by use of a limited degree of power, said parts operating for causing coincident rotation of a basket or dish-holder and for moving or discharging water for cleaning and cleansing the dishes.

Still another object is to provide a machine consisting of few parts which may be conveniently assembled and may be manufactured at a limited expense and will perform all required functions for washing and cleansing in such a manner that the work may be speedily accomplished and that injury or breakage of the dishes may be avoided.

25 The invention includes the use of a tank for supplying hot water charged with soap or other detergent, and a second tank of hot cleansing water, and means for controlling the flow of these waters. Also the invention 30 includes means to cause oscillating movements of the basket so that the dishes therein will be effectively cleaned by the water thrown against them.

With the foregoing objects in view and others to be mentioned the invention presents a new and useful construction, combination and arrangement of parts as described and claimed and as illustrated in the accompanying drawings, it being understood that 40 changes may be made in form, size, proportion of parts and minor details, said changes being within the scope of the invention as claimed.

In the drawing, Fig. 1 is a partly broken 45 away view in longitudinal section showing one embodiment of the invention. Fig. 2 is a perspective view of a rotatable frame.

Fig. 3 is a plan view of a track for the rotatable frame. Fig. 4 is a diagrammatic view for illustrating the track shown in Fig.

3, the circular track being extended longitudinally to clearly show depressions and risers of the track. Fig. 5 is a detail showing the mounting of a vertical shaft upon a rotatable frame.

55 Referring now to the drawing for a more particular description numeral 1 indicates a support or frame upon which is mounted a cylindrical container 2.

60 Numeral 3 indicates a circular track which is mounted in the container 2 near the bottom thereof, said track being provided with depressions 4 and elevated portions or risers 5. Numerals 6 indicate a pair of U-shaped bars or metallic strips disposed crosswise and secured together at their bases and providing a frame or holder 7 having wheels 8 for engaging the track. Numeral 9 indicates a foraminous basket, its sides and bottom preferably being constructed of wire mesh, said basket being removably seated in said holder.

75 Since the wheels 8 are disposed diametrically opposite to each other it will be seen that when one wheel is disposed upon a riser or elevated part 5 of the track the other wheel 8 will be disposed in a depression 4 of said track, each riser being disposed diametrically opposite to a depression, the result in operation being that if the frame which carries the basket is rotated, these parts will have 80 swinging movements transversely of the container 2, and according to the present construction shown, the frame and basket, during operation, would have six swinging movements during one complete rotation of 85 said frame.

The advantages derived from the swinging movements mentioned is to permit the dishes or other contents of the basket to be disposed at various angles to the direction of water which may be thrown against them. While I have shown that the frame and basket have six swinging movements, this feature may be changed, if desired, and the number of these movements may be greater or less than mentioned for each rotation of the frame 7.

I provide a tank 10 for containing water charged with washing-powder or soap, and provide a tank 11 adapted to contain water for cleansing purposes, said tanks being pro-

55

100

vided with strainlers 12 and the water therein being adapted to be heated by suitable burners 13, the tank 10 being in communication with the container 2 subject to the control of a valve 14 and the tank 11 being in communication with said container subject to the control of a valve 15.

Numeral 16 indicates a rotary pump, and at 17 is indicated a horizontal receiving-pipe communicating with the rotary pump, said pipe 17 being in communication with the tank 10 subject to the control of a valve 18 and being in communication with the tank 11 subject to the control of a valve 19.

At 20 is indicated an upright conducting-pipe which communicates with the pump 16, the upper end terminating adjacent to the top of the container 2.

A lid 21 is provided for the cylindrical container 2 and is hingeably mounted thereon as indicated at 22. Numeral 23 indicates a sprinkler which is carried by the lid 21, and at 24 is indicated a hose section in communication with the sprinkler and with the upright conducting-pipe 20.

As thus described it will be seen that if the pump is rotated water may be moved from the tank 10 to be discharged into the container 2 and basket 9 from the sprinkler 23, the valves 14 and 18 being open and the valves 15 and 19 being closed, and the water, of course, may be moved repeatedly through said tank 10 while the valves remain in the condition mentioned, and this is the operation for applying the water to the dishes from the tank 10. The water in this tank thus charged with soap or other detergent and heated by its burner 13 will be discharged from the sprinkler while the basket is rotating, and since the frame or holder 7 and basket 9 have the successive swinging movements mentioned all adhesive substances will be removed from the dishes, and any loose particles of food contained in the water during this operation will be caught by the strainer 12 and may be removed.

The operation for cleansing the dishes is practically the same as already described, the valves 14 and 18 being closed and the valves 15 and 19 being moved to open position.

After the dishes have been cleansed, the lid 21 may be swung to open position and the basket together with the dishes therein may be removed from the holder-frame 7. The tanks 10 and 11 are provided with faucets (not shown) so that the water may be conveniently removed therefrom whenever desired.

The parts shown herein for coincidentally rotating the frame 7 and actuation of the rotary pump 16 consist, in part of a horizontal operating-shaft 25 in suitable bearings, and connected at one of its ends with the core of the rotary pump, these parts being a conventional type and requiring no de-

tailed description. Numeral 26 indicates a vertical shaft since its gear-wheel 27 engages the gear-wheel 28 of said shaft 25.

The means shown for rotating the operating-shaft 25 consist of a hand-wheel 29 mounted on a stub-shaft 30, a band 31 being mounted upon and adapted to be moved by the hand-wheel 29 for rotating the wheel 32 and operating-shaft, said wheel 32 being mounted on that end of the operating-shaft opposite to the rotary pump.

Any suitable coupling may be provided for a connection of the vertical shaft 26 with the base of the frame 7 of the basket-holder which will permit said frame 7 to have the swinging movements mentioned transversely of the container 2, the coupling shown herein being the flat tongue 33 which projects downwardly from the base of the holder-frame 7 at its middle part, said tongue being removably mounted between the terminal wings 34 of the vertical shaft 26, a bolt or pivot-pin 35 being used for connecting the wings with said tongue.

The bottom of the container 2 is provided, centrally thereof, with a tubular bearing-member 36 for the vertical shaft, said tube being provided with packing 37 to prevent leakage of any water from the container.

In operation, water may flow freely through the container 2 subject to the control of the valves 14 and 15 and in operation, a few minutes only are required for completely washing and cleansing a basket of dishes.

Numeral 38 indicates a grid-member 100 adapted to be disposed in the basket 9, said grid being provided with slots (not shown) for receiving the dishes or their edges.

I claim as my invention,—

In a dish washing machine, a liquid container, a circular track therein having alternate diametrically opposed risers and depressions, a frame having diametrically opposed wheels on said track, a foraminated basket in said frame, means for rotating said frame, and means for spraying liquid onto said basket.

In testimony whereof, I have affixed my signature.

JOHN H. MONTGOMERY. 115
